FUEL INJECTION PUMP

George A. Gillen, New York, N. Y.

Application October 23, 1936, Serial No. 107,169

2 Claims. (Cl. 103—41)

This invention relates to internal combustion engines of the fuel injection type.

Special objects of the invention are to effect an accurate metering of the fuel to correspond with varying load requirements and to accomplish this with sturdy, simple and practical apparatus.

These and other desirable objects are attained by novel features of construction, combinations and relations of parts hereinafter disclosed and broadly claimed.

The drawing accompanying and forming part of the specification illustrates one simple practical embodiment of the invention, but it will be understood that the structure may be modified and changed in various ways, all within the true intent and broad scope of the invention.

Figure 1 is a broken and longitudinal sectional view of one form of the apparatus.

Figure 2 is a broken plan view of the same partly in section, as on substantially the plane of line 2—2 of Figure 1.

These views illustrate the injectors for a four-cylinder engine and special relief valves which can be opened sooner or later in the cycle to bypass greater or less portions of the fuel to suit load requirements on the engine.

The injectors are designated 3 and as shown particularly at the left in Figure 1, they consist in each instance of a hollow piston 4 sliding over a fixed cylinder 5 having an intake port 6 connected through a check valve 7 with a supply manifold 8. The latter is indicated as connected by a pipe 9 with a liquid fuel tank 10.

The hollow piston is suitably sealed over the fixed cylinder, as by means of packing rings indicated at 11, and motion is imparted to the piston, in one direction by the spring 12 surrounding and acting against a flange 13 at the outer end of the piston and in the opposite, injecting direction by a face cam 14 bearing on the head or closed end of the piston.

The injector cam 14 is shown as forming part of the head or enlargement 15 on the upper end of a sleeve 16 journaled in a casing 17 and suitably supported, as by means of radial and thrust bearings 18, 19. This cam sleeve is shown as rotated by an engine driven shaft 20 carrying a bevel pinion 21 in mesh with a corresponding ring gear 22 fixed to the lower end of the sleeve.

The several injectors are shown as located in a cavity or chamber enlargement 23 in the upper end of the casing or hollow base structure 17 and the piston elements of the several pumps

are shown as carried by a detachable head structure 24 closing the upper end of this chamber.

With rotation of the cam sleeve 16, the hollow pump pistons will be reciprocated and in so doing, they will, in the lowering or intake stroke, take in liquid fuel through the intake passages 6 and, on the reverse, upward stroke, will force liquid out through the discharge ports 25 and through the feed lines 26 to the atomizer nozzles or fuel injecting devices in the engine cylinders.

To predetermine the amount of liquid which each injector will pump to the cylinder with which it is connected, each pump cylinder has a relief passage 27 leading to a valve body 28, containing a valve 29 urged in a closing direction by spring 30, but adapted to be opened by an oppositely acting rocker 31 carrying a roll 32 for engagement with a cam 33.

The relief cam 33 is shown as carried by the upper end of a sleeve 34 slidably keyed at 35 in the pump cam sleeve 16 so as to rotate with the latter and the inner cam sleeve is shown as longitudinally adjustable by having a hub flange 36 engaged by the yoke 37 at one end of a lever 38 pivoted at 39 and carrying at its opposite end, 25 a nut element 40 engaged by the adjusting screw shaft 41.

The adjusting shaft 41 may be equipped with a suitable handle for turning the same or the adjustment of this shaft may be effected automatically as required for desired engine performance. It will be clear that with longitudinal adjustment of sleeve 34, the relief cam 33 may be raised or lowered and hence be caused to open the relief valves sooner or later in the cycle of operations. The parts may be so designed that the relief cam may be withdrawn so far as not to actuate the relief valves at all and in which event the injectors will pump substantially their full displacement. The range of adjustment may be such that the relief cam may be advanced to such an extent as to open the relief valves at the commencement of the pumping stroke to thereby prevent any pumping action. Adjustments between these extremes will regulate the amount of liquid pumped by each injector and such regulation may be made instantly and at any time.

The several relief valves may be connected to discharge into a common relief manifold 42 and the latter may be connected to discharge through 50 a return line 43 into the fuel tank 10.

The adjustment of the cam varies the point of engagement between the cam and rockers and this, with proper angle and contour of cam, may be utilized to effect any desired "lead" or "lag" 55

in the relief valve operation, as might be desirable for different engine speeds and loads.

While the construction illustrated may be considered as a preferred form at the present time, it will be appreciated that construction may be altered to suit different conditions and requirements. The terms employed herein have, therefore, been used in a descriptive rather than in a limiting sense, except possibly as limitations may 10 be imposed by the state of the prior art.

I claim:

1. In combination, a casing having a generally cylindrical seat, a sleeve journaled to rotate in said seat and having a cam at one end, a cover 15 applied to the end of the casing over said cam end of the sleeve, fuel injector pumps in concentric relation on said cover and operatively opposed to said cam on the end of said rotating sleeve, a circular series of relief valves for said injector pumps

and concentrically related to said pumps, a cam element slidably keyed in said rotating sleeve in position to actuate said relief valves and means for adjusting said sliding cam element longitudinally in said rotating cam sleeve.

2. In combination, rotating concentric cam sleeves slidably keyed together and shiftable one in respect to the other, cam elements on the adjoining ends of said sleeves, fuel injector pumps supported in position to be actuated by the cam element on the end of one of said sleeves, relief valves for said injector pumps supported for actuation by the cam element on the end of the other of said sleeves, means for effecting rotation of said sleeves and means for effecting relative 1 longitudinal shifting of one sleeve in respect to the other.

GEORGE A. GILLEN.
